W. B. S. WHALEY,
AUTOMATIC AND REGULABLE LIQUID FUEL INJECTION VALVE,
APPLICATION FILED FEB. 19, 1920.

Patented Mar. 28, 1922.

Fig. 1.

UNITED STATES PATENT OFFICE.

WILLIAM BURROUGHS SMITH WHALEY, OF NEW YORK, N. Y., ASSIGNOR TO DAVID LICHTENSTEIN, OF BOSTON, MASSACHUSETTS.

AUTOMATIC AND REGULABLE LIQUID-FUEL INJECTION VALVE.

1,411,143.

Specification of Letters Patent. Patented Mar. 28, 1922.

Application filed February 19, 1920. Serial No. 359,827.

To all whom it may concern:

Be it known that I, WILLIAM B. SMITH WHALEY, a citizen of the United States, and a resident of New York city, in the county 5 of New York and State of New York, have invented a new and useful Automatic and Regulable Liquid-Fuel Injection Valve, of which the following is a specification, reference being had to the accompanying sheet 10 of drawing forming part thereof.

This invention relates to liquid fuel injection valves for internal combustion engines, and has for its object to provide an automatically operated device which is simple in construction, absolutely reliable in its 15 operations, and may be employed with either two or four cycle engines of any power or speed, whether operating on gasoline, heavier oils, or other forms of liquid fuel.

Another object of the invention is to provide an oil injection device as aforesaid, which receives its impulse from the compression pressure within the cylinder with which the same is associated, and is controlled 25 automatically thereby to yield a corresponding injection of fuel therein to meet the peculiar needs of the engine.

Another object of the invention is to provide a fuel injection valve device which operates automatically in accordance with the compression pressure within the cylinder, and eliminates the need for valve gears usually attending oil injection devices.

Still another object of the invention is to provide a device embodying the aforesaid features thereto, which is regulable and controllable, and possesses a governing feature for the engine.

To these as well as other ends my invention consists of the novel features of construction, combination, and arrangement of parts described in the following specification and particularly pointed out in the subjoined claims.

The terms employed herein are used in the generic and descriptive sense to designate the elements illustrated, and are therefore not primarily intended as terms of limitation.

In order to illustrate the invention, I have shown in the drawing one embodiment thereof, but without being limited thereto, wherein:

Fig. 1 represents a part sectional and part fragmentary view showing the device diagrammatically coupled with an oil pump

and applied to the header of the engine cylinder;

Fig. 2 represents a fragmentary plan view of Fig. 1;

Fig. 3 represents a sectional view taken on line 3--3 on Fig. 1;

Fig. 4 represents an enlarged sectional view of the oil regulating valve mechanism of the device; and

Fig. 5 represents a bottom view of the spray valve or cylinder end of the device.

Like numerals refer to like parts throughout the several views of the drawing.

The numeral 10 represents a cylinder of an internal combustion engine in which 11 is the bore and 12 the compression chamber. 13 represents the header of the cylinder which may be made integral therewith or separate therefrom (as shown in the drawing), and rigidly secured thereto. Said 75 header 13 is preferably water jacketed, as shown, and provided with the plunger bore 14 and the compression duct 15. 16 represents the movable and tubular plunger member which fits within the header plunger 80 bore 14 with suitable clearance to yield the desired fit therebetween for enabling the plunger member 16 to move up and down therein, as required by the operations of the device. Said plunger member 16 is preferably provided with the internal conical valve seat 17 on the cylinder end thereof, and with the seating flange 18 on the opposite and free end, where said flange 18 is cupped to receive the lower end of the timing spring 19 90 for aligning the same in the device. The plunger member 16 is further preferably provided at the valve or cylinder end thereof with the annular chamber 20 which communicates through the radial and angularly 95 disposed vent holes 21 with the compression chamber 12 of the engine cylinder. 22 represents a threaded section provided in the plunger member which receives the clamping collar 23 and which collar clamps the 100 sealing diaphragm 24 to the seat provided therefor in the plunger member, as shown in Fig. 1; said diaphragm being preferably a copper ring yielding slightly to the movement between said plunger member 16 and 105 the conical or injection valve stem 25 as required in the device. 26 represents the conical or injecting valve which is preferably made integral with said valve stem 25, as shown, and provided with the oil plunger 110

bore 27, which telescopingly receives the fixed oil tube 28. 29 represents the oil outlet duct of the valve stem 25 and communicates with the radial spray outlets 30 which are open to the annular oil groove 31 provided in the valve stem 25 above the valve seat 32, as shown. 33 represents the valve stem clamping tube which seals the diaphragm 24 in secured position with the valve stem 25 by means of the nut 34. 35 represents the valve spring (expansion) which is adjusted normally to hold the valve 26 seated with the plunger 14.

36 represents the valve casing which houses the timing spring 19 and provides the seat 37 for the plunger flange 18 and the plunger packing gland 38, as shown; said valve casing being preferably open at the top and closed at the bottom, as shown.

40 represents the oil receiving head of the device, which is preferably made of composition or steel, so that the oil will not permeate under high pressure, and is flanged to fit and securely seal the top of the valve casing 36, as by means of the bolts 41. Said oil receiving head 40 is preferably designed with the timing spring guide collar 42, and carries the oil tube 28 fixed thereto, the latter being open to the oil duct 43 which leads to the vent cock 44 through which air from the chamber 27 may be drawn off, as may be found necessary.

Communicating with the oil duct 43 is the oil duct 45 which is open to the regulating valve duct 46 through the regulable bypass valve 47 and the delivery oil duct 48 through the ball valve 49 which is held by the expansion spring 50 and is gauged to lift under a pressure exceeding, say 25 pounds per square inch for a pressure of, say 25 pounds to the oil system. 51 represents the oil feed pipe of the device, which connects with the pump 52 through the regulable pump discharge valve 53, as shown.

55 represents the tubular compression duct stud, which threadedly engages at the lower end with the header 13, and is threaded at the top to receive the nut 56 whereby said stud serves to assist in clamping the oil receiving head 40 and the casing 36 together with the head 13. Said stud is preferably provided with the valve seat 57 and the vents 58 and 59, said vents opening into the chamber 60 of the oil header 40 which is open to the chamber 61 of the casing member 36, as shown in Fig. 1.

62 represents the compression duct plunger valve, which is ported to allow communication between the compression duct 15 and the vent 58 which opens into the chamber 60. Said valve 62 is provided with the stem 63 which is guided in the fixed collar 64, which is secured to the stud 55 and carries secured thereto the spring collar 65 against which the expansion spring 66 acts to normally

seat the valve 62. The other end of said spring 66 engages with the adjusting nut 67 through which the valve stem 63 is exposed and squared to allow for the turning of the valve 62 for adjustment and regulating purposes.

68 represents the oil bypass valve plug which is rigidly secured with the oil head 40, as by being securely screwed therein and held by the check nut 69. Said plug 68 rotatably holds therein the valve 47 which also protrudes through the plug bonnet 70 for regulating and adjustment purposes. The valve is recessed, as shown, and carries secured thereto the spring collar 71 against which the expansion spring 72 acts. The bonnet 70 is adjustable with reference to the plug for adjusting the tension on said bypass spring 72.

Having thus described the parts of the invention in detail, it will be noted that the timing spring should be accurately made and adjusted for a pressure to compensate the pressure in the diameter of the valve end of the plunger 16 with the valve 26 seated and so as to permit the plunger to move at the earliest lead desired. The timing spring has a fixed tension and requires no adjustment.

It will also be noted that the valve spring 35 is adjusted to normally hold the valve 26 seated against the highest pressure in the oil system, so that said valve 26 cannot be opened normally except through the movement of the plunger 16. The valve spring 35 may also be provided with a fixed tension, 100 and need not be adjustable.

It will also be noted that the bypass valve 47 is both rotatable and slidale, and is provided with a tension spring 72 which is gauged normally to hold the valve 47 in proximity with the bypass duct 46, as shown in Fig. 1. The rotatable feature thereof permits of regulating the bypass port, which regulates the oil pressure in the plunger bore 27 while the slidale feature thereof allows for the automatic opening of the bypass port when the oil pressure in the plunger bore 27 rises beyond the maximum limit therefor. Should the pressure in the cylinder 11 rise above the safe maximum for which the engine is designed, the pressure would act on the area of the valve 26, causing the valve 26 to close, and consequently the pressure in the plunger bore 27 would rise because of the reduced head on the atomized oil therein. Such a rise of pressure is at once transmitted to the bypass valve 47 which forces same away from the oil duct bypass port 46 and results in stopping the delivery of fuel to the engine. To accomplish the same, the tension on the spring 72 is set about 5 pounds per square inch in excess of the desired pressure on the oil in the oil reservoir or plunger bore 27.

It will also be noted that the regulating

valve 62, which connects the compression space 12 of the cylinder through the duct 15 and vent 58 with the valve casing chamber 61, is designed so that a fixed opening can be made by adjustment to maintain any desired pressure in the spring chamber 61 to increase or decrease the period of lift to the plunger member 16, by compensating in part the compression pressure in the cylinder 11 and reducing the period or causing the valve 62 to lift later. The valve 62 is so adjusted that the tension on its spring 66 holds against any but that pressure rise in the cylinder that would cause rupture therein, when the valve 62 automatically lifts away from its seat 57 and exposes the chamber 61 to the higher pressure, which would compensate the whole action of the plunger 16 and prevent it from delivering fuel to the cylinder until normal pressure is again resumed.

It will also be noted that the oil system feeding to the device, as suggested, may be 25 pounds, or different, according as may be desired, and that the bypass valve 53 may be coupled with and automatically regulated by the governing mechanism of the engine; it being, however, here understood that the valve 53 may be normally set to discharge oil from the pump 52 which first reaches a predetermined pressure.

It will also be noted that the timing spring chamber 61 may be filled with oil, if desired, for cushioning and lubricating the available working parts of the device, and that the plunger member 16 may be allowed a substantial lift, as say, $\frac{5}{8}$ " normal and 1" maximum for a device of the proportion shown in the drawing.

The compression pressure of the engine thus acts on the plunger 16 and imparts the lifting impulse thereto, carrying with it for a period the valve 26 seated and closed. The displacement of the valve lift, under these circumstances, increases the pressure on the oil in the plunger bore 27 to an extent which forces the valve 26 to become unseated from the plunger seat 17, when the oil from within the plunger bore 27 is forced out through the set of radial oil vents 30 and is atomized and injected under high pressure into the cylinder. The yield to the diaphragm 24 determines the distance of opening of said spray or injecting valve 26. The compression ring 20 acts as a reservoir for compressed air, receiving same through the decarbonizing ducts 21, which open to the cylinder just below the valve seat 32 (when the valve 26 is seated), and thus furnishes oxygen on expansion to consume the surplus carbon or oil at the valve which might otherwise cause trouble by gumming or carbonizing. The device is thus automatic in its operations, and is regulable, controlled by the pressure impulses occurring within the cylinder, and

automatically supplied the same with the necessary fuel to meet the various working requirements thereof.

The valve movement is designed to maintain at all times a head on the atomized spray, of say double the compression pressure in the cylinder, thus insuring both impregnation and turbulence in the combustion chamber of the engine.

From the foregoing description of parts and functions, it will be understood that until compression is attained in the cylinder no fuel will be delivered therein through the device; the delivering of fuel being controlled entirely by the demands of the heat influx to maintain the desired M. E. P. according to load. If the compression pressure in the cylinder, from any cause, becomes increased or diminished, which would naturally affect the condition of the media in the cylinder, the valve mechanism of the within device would automatically adjust itself to cause the condition to resume the normal, which is controlled by the pressure in the pump system, regulated by the governor of the engine, or by the hand regulated bypass 47 to control all load and speed requirements.

The pressure in the pump system ranges from, say 25 pounds, under which no oil would be delivered through the spring-held ball valve 49 up to say 200 pounds per square inch, at which pressure the pressure in the plunger bore 27 would exceed the resisting pressure by the bypass valve spring 72, and instantly open the full bypass; thus relieving all the pressure in the plunger bore 27 required to inject the atomized oil through the valve 26 and automatically cut the fuel from the engine. The pressure in the spring chamber 62 is similarly affected by any rise in pressure in the cylinder during the injection period, and dampens or stops the action on the plunger member 16, so that here again the supply of fuel is automatically reduced or cut off. Hence, the range of pressure in the oil delivering system, from say 25 pounds as a minimum, to say 200 pounds as a maximum, gives a range of control for all speeds or variations in loads in the engine, controllable either by automatically varying the stroke of the plunger member 16, or plunger on the oil pump by shaft governing means, but, as will be understood, by hand or governing means applied to open or close a bypass from the supply to the suction of the pump.

The range of pressures available through the pressure range in the oil supply system, permits a very wide and flexible range of control for all loads, and from no load to full load, or the reverse an instantaneous control of conditions. The pressure conditions in the cylinder will always offer the initial means of control to preserve safety

and uniformity of operations, and these are in turn followed up by speed or governing means as a secondary safeguard to insure smooth and uniform regulation.

5 No injection of fuel can anticipate the necessary compression to ignite it, as until the predetermined, constant working pressure at which the plunger 16 begins to act is produced by adiabatic compression, no 10 fuel can be delivered to maintain the pressure by heat influx to the point of cut-off determined by the delivery from the valve, and when adiabatic expansion occurs the valve will close and admit no more fuel to 15 the cycle.

So that constant pressure at all times is assured, and no excess of fuel can be delivered beyond that necessary to cause this result. There, therefore, can be no after 20 burning or carbonization when the oil bypass is once set for the maximum supply at the full load rating of the engine to properly be consumed by the oxygen furnished by the air means for this full load 25 rating.

The hazard of prematurely is thereby reduced to a minimum or entirely obviated, and the maximum working compression and pressures cannot be exceeded at any time. 30 Therefore, the necessity of anticipating in the design of the engine those abnormal weights caused by having to design the engines for these abnormal pressure conditions is entirely eliminated. The fuel is at all 35 times, during operations, delivered in the nearest state for perfect combustion and splitting, both by temperature prior to injection and atomization and turbulence at injection to cause perfect combustion.

40 The fuel is introduced into the cylinder at the most advantageous point, always automatically controlled by the valve. Only that amount of fuel to maintain constant pressure is introduced. Complete combustion is 45 assured and is at all times automatically controlled by the device. Combustion takes place at the conical atomizing zone; therefore no carbonizing, sutting or gumming can occur. Atomization is always the same regardless of the oil used. There are practically no parts subject to shock, fatigue or 50 rupture. All parts are easily accessible, and the life of the device should be no less than the other parts of the engine.

55 While the preferred embodiments of my invention have been described in detail, it will be understood that I do not wish to be limited to the particular construction set forth, since various changes in the form, 60 material, proportions, arrangement of parts, and in the details of construction, may be resorted to without departing from the spirit and scope of the invention, or destroying any of the advantages contained in the

same, heretofore described and defined in 65 the subjoined claims.

Having thus described my invention in detail, what I claim as new is:

1. An automatically controlled fuel injection valve comprising a floatable plunger member exposed to the pressures within the combustion chamber of the engine and adapted to be actuated thereby; a floating oil carrying and discharge member, telescopingly fitting said plunger member, provided with a contracting oil reservoir therein which is open to the oil system of the engine, and a sealing header which normally seats with said plunger member for preventing discharge therebetween of oil carried in said oil carrying and discharge member and otherwise to unseat for effecting an atomizing effect to the discharging oil therebetween; and yieldable coupling means normally engaging said plunger member with 75 said atomizing valve member to cause the latter to floatably operate in sealed relationship therewith, but to be relatively free to permit said valve member to unseat from said plunger member when the pressure on 80 the oil in the reservoir exceeds the actuating pressure operating said plunger member for effecting the aforesaid atomizing discharge feature.

2. An automatically controlled fuel injection valve comprising a floatable plunger member exposed to the pressures within the combustion chamber of the engine and adapted to be actuated thereby; a floating atomizing valve member, telescopingly fitting said plunger member, provided with a contracting oil reservoir therein which is open to the oil system of the engine at one end thereof and to the combustion chamber at the other end, and a sealing valve which 100 normally seats with said plunger member for effecting a closure to said floating valve member and otherwise to unseat for effecting a spray opening therebetween for discharging the oil therethrough; yieldable coupling means normally engaging said plunger member with said atomizing valve member to floatably operate therewith in sealed relationship, otherwise to permit said valve member to unseat from said plunger member to effect the spray opening therebetween when the pressure on the oil in the reservoir exceeds the actuating pressure operating 110 said plunger member; yieldable resisting means provided said floatable plunger 115 adapted to restrict same against motion under a predetermined pressure in the combustion chamber; and a regulable bypass means controlling the relief from the oil reservoir back to the oil supply.

3. An automatically controlled fuel injection valve comprising a floatable plunger member exposed to the pressures within

- the combustion chamber of the engine and adapted to be actuated thereby; a floating atomizing valve member, telescopingly fitting and floatably coupled with said plunger member, provided with a contracting oil reservoir for housing oil therein, which reservoir is open to the oil system of the engine, and a sealing header which normally seats with said plunger member for preventing discharge therebetween and for otherwise effecting an atomizing discharge of oil from the reservoir therebetween; yieldable coupling means normally engaging said plunger member with said atomizing valve member to floatably operate therewith in sealed relationship and otherwise to unseat for effecting the aforesaid atomizing feature, when the pressure on the oil in the reservoir exceeds the actuating pressure operating said plunger member; yieldable resisting means provided said floatable plunger adapted to restrict same against motion under a predetermined pressure in the combustion chamber; a regulable bypass means controlling the relief from the oil reservoir back to the oil supply; and means for controlling the cylinder pressure on the resisting side of said floatable plunger member.
4. A fuel oil injecting device for internal combustion engines, comprising a floatable valve carrying member, communicating with the combustion chamber of the engine actuated and controlled by the pressures within the combustion chamber; a telescoping plunger valve member floatably carried in said floatable valve carrying member, open to the oil system of the engine, provided with an oil reservoir, and a valve header also exposed to the combustion chamber and normally seating with said valve carrying member for sealing said reservoir and otherwise unseating for effecting a discharge for said reservoir into said combustion chamber; yieldable coupling means engaging said plunger valve member with said valve carrying member normally adapted to seat the valve of the former with the latter and otherwise to permit the unseating of said valve for discharging purposes as aforesaid, when the pressure in the oil reservoir (due to displacement) effected by the movement of the valve carrying member, overcomes the seating force of the yieldable coupling means and cylinder pressure exerted against the plunger valve member.
5. An automatic fuel oil injecting valve device having telescopingly related hollow valve and valve seating members, each being floatably exposed to the pressures within the cylinder and yieldably coupled together for normally preserving a sealed relationship therebetween and otherwise effecting a slight lagging feature therebetween to provide a discharge opening for the device; means provided said valve seating member to resist the cylinder pressure up to a predetermined point before the floating or lifting action of the seating member begins; means connecting said valve member with the oil supply forming a contractible oil reservoir with said valve member, said oil reservoir having an outlet in the valve head of said valve member and adapted to force said valve member to lag and unseat from the valve seating member to discharge oil therebetween when the pressure in said reservoir exceeds the operating pressures of said seating member.
6. A fuel oil injecting device for internal combustion engines, comprising a main tubular plunger member slidably supported in means provided therefor and having an end thereof open to the combustion chamber of the engine with said end provided with an internal conical valve seat; yielding means associated with the opposite and free end of said tubular plunger member adapted to prevent motion thereto under predetermined pressures prevailing in said combustion chamber; a valve plunger member slidably fitted within said tubular plunger member provided with an oil reservoir therein and a discharging valve header on the combustion chamber end thereof having discharge outlets communicating with said reservoir and adapted to fit and seat with the conical seat provided therefor in said tubular plunger member for sealing the reservoir outlets provided in said header, said reservoir having a bore which slidably fits over a fixed tubular oil feeding plunger which is coupled with the oil system; yieldable coupling means engaging said main tubular plunger member with said oil reservoir valve plunger adapted to normally hold the two in seated and sealed relationship under predetermined pressures actuating said plungers and otherwise to wink and permit lagging therebetween for slightly unseating the two for discharging a spray of oil from the reservoir into the combustion chamber.
7. A fuel oil injecting device for internal combustion engines, comprising a main tubular plunger member slidably supported in means provided therefor and having an end thereof open to the combustion chamber of the engine with said end provided with an internal conical valve seat; yielding means associated with the opposite and free end of said tubular plunger member adapted to prevent motion thereto under predetermined pressures prevailing in said combustion chamber; a valve plunger member slidably fitted within said tubular plunger member provided with an oil reservoir therein and a discharging valve header on the combustion chamber end thereof, having discharge outlets communicating with said reservoir and adapted to fit and seat with the conical seat provided therefor in said

tubular plunger member for sealing the reservoir outlets provided in said header, said reservoir having a bore which slidably fits over a fixed tubular oil feeding plunger 5 which is coupled with the oil system; yieldable coupling means engaging said main tubular plunger member with said oil reservoir valve plunger member adapted to normally hold the two in seated and sealed relationship under predetermined pressures 10 actuating said plungers and otherwise to give slightly to permit the unseating of the two for discharging a spray of oil from the reservoir into the combustion chamber there- 15 between; means controlling the oil supply to said fixed oil plunger; and means for regulably bypassing the oil from said oil plunger to the oil supply.

8. A fuel oil injecting device for internal combustion engines, comprising a main tubular plunger member slidably supported in means provided therefor and having an end thereof open to the combustion chamber of the engine with said end provided with 20 an internal conical valve seat; yielding means associated with the opposite and free end of said tubular plunger member adapted to prevent motion thereto under predetermined pressures prevailing in said combustion chamber; an oil reservoir valve plunger slidably fitted within said tubular plunger member provided with a discharging valve head on the combustion chamber end thereof adapted to fit and seat with the 25 conical seat provided therefor in said tubular plunger member for sealing the reservoir outlets provided in said header, said reservoir having a bore which slidably fits over a fixed tubular oil feeding plunger 30 which is coupled with the oil system; yieldable coupling means engaging said main tubular plunger member with said oil reservoir valve plunger adapted to normally hold the two in seated and sealed relationship 35 under predetermined pressures actuating said plungers and otherwise to permit the unseating of the two for discharging a charge of oil from the reservoir into the combustion chamber; and means for regulably subjecting the free ends of said main and reservoir plungers to the combustion chamber pressures.

9. A fuel oil injecting device for internal combustion engines, comprising a main tubular plunger member slidably supported in means provided therefor and having an end thereof open to the combustion chamber of the engine with said end provided with an 40 internal conical valve seat; yielding means associated with the opposite and free end of said tubular plunger member adapted to prevent motion thereto under predetermined pressures prevailing in said combustion chamber; an oil reservoir valve plunger slidably fitted within said tubular plunger mem- 45

ber provided with a discharging valve head on the combustion chamber end thereof, adapted to fit and seat with the conical seat provided therefor in said tubular plunger member for sealing the reservoir outlets provided in said header, said reservoir having a bore which slidably fits over a fixed tubular oil feeding plunger which is coupled with the oil system; yieldable coupling means engaging said main tubular plunger member with said oil reservoir valve plunger adapted to normally hold the two in seated and sealed relationship under predetermined pressures actuating said plungers and otherwise to permit the unseating of the two for discharging a charge of oil from the reservoir into the combustion chamber; means controlling the oil supply to said fixed oil plunger; means for regulably bypassing the oil from said oil plunger to the oil supply; and means for regulably subjecting the free ends of said main and reservoir plungers to the combustion chamber pressures.

10. A fuel oil injecting device for internal combustion engines, comprising a main tubular plunger member slidably supported in means provided therefor and having an end thereof open to the combustion chamber of the engine with said end provided with an internal conical valve seat; yielding means associated with the opposite and free end of said tubular plunger member adapted to prevent motion thereto under predetermined pressures prevailing in said combustion chamber; an oil reservoir valve plunger slidably fitted within said tubular plunger member provided with a discharging valve head on the combustion chamber end thereof adapted to fit and seat with the conical seat provided therefor in said tubular plunger member for sealing the reservoir outlets provided in said header, said reservoir having a bore which slidably fits over a fixed tubular oil feeding plunger which is coupled with the oil system; yieldable coupling means engaging said main tubular plunger member with said oil reservoir valve plunger adapted to normally hold the two in seated and sealed relationship under predetermined pressures actuating said plungers and otherwise to permit the unseating of the two for discharging a charge of oil from the reservoir into the combustion chamber; means controlling the oil supply to said fixed plunger; and means for regulably bypassing and automatically opening the oil supply in the device to the main oil supply for the engine.

11. A fuel oil injecting device for internal combustion engines, comprising a main tubular plunger member slidably supported in means provided therefor and having an end thereof open to the combustion chamber of the engine with said end provided with an internal conical valve seat; yielding means

associated with the opposite and free end of said tubular plunger member adapted to prevent motion thereto under predetermined pressures prevailing in said combustion chamber; an oil reservoir valve plunger slidably fitted within said tubular plunger member provided with a discharging valve head on the combustion chamber end thereof adapted to fit and seat with the conical seat provided therefor in said tubular plunger member for sealing the reservoir outlets provided in said header, said reservoir having a bore which slidably fits over a fixed tubular oil feeding plunger which is coupled with the oil system; yieldable coupling means engaging said main tubular plunger member with said oil reservoir valve plunger adapted to normally hold the two in seated and sealed relationship under predetermined pressures actuating said plungers and otherwise to permit the unseating of the two for discharging a charge of oil from the reservoir into the combustion chamber; means controlling the oil supply to said fixed plunger; means for regulably bypassing and automatically opening the oil supply in the device to the main oil supply for the engine; and means for regulably and automatically subjecting the free ends of said main and reservoir plungers to the combustion chamber pressures.

12. An oil injecting device for internal combustion engines, comprising correlated and telescoping plunger members floatably coupled in respect to each other and in respect to the engine cylinder, with both of said plunger members exposed to the cylinder pressures and adapted to be actuated thereby under predetermined cylinder pressures; yieldable means provided the outer of said correlated and telescoping plunger member gauged to resist the cylinder pressure thereagainst to a predetermined point and then allow for a floating and lifting action to said outer plunger member; a valve header provided the inner of said plunger members, adapted to seat with said outer plunger member and open into the cylinder; an oil reservoir provided in said inner plunger member opening to the valve header thereof and sealed thereby by the seating thereof; a fixed oil feeding tubular connection receiving the oil from the system telescopingly fitted within said reservoir provided said inner plunger member and adapted to contract the reservoir with the lifting of said plunger members for building up the pressure in said oil reservoir to force the valve header to unseat and inject oil into the cylinder; and yieldable coupling means normally engaging the plunger members in seated relationship with each other and otherwise allowing for the unseating of the valve header during the lift of the outer plunger, when the reservoir pressure pre-

vails against the holding force of said yieldable coupling means.

13. An oil injecting device for internal combustion engines, comprising correlated and telescoping plunger members floatably coupled in respect to each other and in respect to the engine cylinder with both of said plunger members exposed to the cylinder pressures and adapted to be actuated thereby under predetermined cylinder pressures; yieldable means provided the outer of said correlated and telescoping plunger member gauged to resist the cylinder pressure thereagainst to a predetermined point and then allow for a floating and lifting action to said outer plunger member; a valve header provided the inner of said plunger members adapted to seat with said outer plunger member and open into the cylinder an oil reservoir provided in said inner plunger member opening to the valve header thereof and sealed thereby by the seating thereof; a fixed oil feeding tubular connection receiving the oil from the system telescopingly fitted within said reservoir provided said inner plunger member and adapted to contract the reservoir with the lifting of said plunger members for building up the pressure in said oil reservoir to force the valve header to unseat and inject oil into the cylinder; yieldable coupling means normally engaging the plunger members in seated relationship with each other and otherwise allowing for the unseating of the valve header during the lift of the outer plunger, when the reservoir pressure prevails against the holding force of said yieldable coupling means; housing means encasing the free ends of said plunger members and open through a bypass to the combustion chamber of the cylinder; regulable valve means adapted to control the said cylinder bypass; and a regulable oil bypass valve means intercepting between said oil feeding connection and the oil pump for relieving the pressure in the oil reservoir of the inner plunger member.

14. An oil injecting device for internal combustion engines, comprising correlated and telescoping plunger members floatably coupled in respect to each other and in respect to the engine cylinder pressures and adapted to be actuated thereby under predetermined cylinder pressures; yieldable means provided the outer of said correlated and telescoping plunger member gauged to resist the cylinder pressure thereagainst to a predetermined point and then allow for a floating and lifting action to said outer plunger member; a valve header provided the inner of said plunger members adapted to seat with said outer plunger member and open into the cylinder; an oil reservoir provided in said inner plunger member opening to the valve header thereof and sealed

thereby by the seating thereof; a fixed oil feeding tubular connection receiving the oil from the system telescopingly fitted within said reservoir provided said inner plunger member and adapted to contract the reservoir with the lifting of said plunger members for building up the pressure in said oil reservoir to force the valve header to unseat and inject oil into the cylinder; yieldable coupling means normally engaging the plunger members in seated relationship with each other and otherwise allowing for the unseating of the valve header during the lift of the outer plunger when the reservoir pressure 5 prevails against the holding force of said yieldable coupling means; housing means encasing the free ends of said plunger member and open through a bypass duct to the engine cylinder; combined regulable, 10 and pressure actuated bypass valve means controlling said cylinder bypass duct; and combined regulable and pressure actuated oil valve means adapted to control the oil pressure in the oil reservoir as required under the peculiar working conditions of the 15 engine.

15. A fuel oil injecting device for internal combustion engines, comprising a floatable tubular plunger member provided with a 20 vented valve sealing end which is exposed to the combustion chamber of the engine and floatably operated by the pressures prevailing therein; a yieldable resisting member associated with the opposite end of said plunger member and adapted to hold same 25 against movement under predetermined combustion chamber pressures; a cylindrical valve member adapted to floatably fit within said tubular plunger and provided on one 30 end with a valve header adapted to clear the vents in said plunger member when seated therewith and an oil plunger bore on the other end, said bore having spray outlets provided therein in proximity with the valve header for discharging purposes when the latter becomes unseated; yieldable coupling 35 means, yieldably coupling said plunger member with said valve member adapted to normally preserve a seated relationship therebetween; a stationary oil delivery tubular plunger member fitting said oil plunger bore of said valve member to permit the valve member to float thereon and opening the bore of the same to the oil supply of the device. 40

16. A fuel oil injecting device for internal combustion engines, comprising a floatable tubular plunger member provided with a vented valve sealing end which is exposed to the combustion chamber of the engine and floatably operated by the pressures prevailing therein; a yieldable resisting member associated with the opposite end of said plunger member and adapted to hold same 45 against movement under predetermined 50

combustion chamber pressures; a cylindrical valve member adapted to floatably fit within said tubular plunger and provided on one end with a valve header adapted to clear the vents in said plunger member when seated therewith and an oil plunger bore on the other end, said bore having spray outlets provided therein in proximity with the valve header for discharging purposes when the latter becomes unseated; yieldable coupling 55 means yieldably coupling said plunger member with said valve member adapted to normally preserve a seated relationship therebetween; a stationary oil delivery tubular plunger member fitting said oil plunger bore of said valve member to permit the valve member to float thereon and opening the bore of the same to the oil supply of the device; a casing member housing said yieldable resisting member and the free ends of said plunger and valve members and open to the combustion chamber by a duct provided therefor for compensating the cylinder pressures directed against the cylinder ends of said plunger and valve members; and a 60 regulable and automatically operated bypass mechanism intercepting said bypass duct for regulably controlling the pressure in said casing member and for automatically exposing same to the full pressure of the combustion chamber, according as may be necessary. 65

17. A fuel oil injecting device for internal combustion engines, comprising a floatable tubular plunger member provided with a vented valve sealing end which is exposed to the combustion chamber of the engine and floatably operated by the pressures prevailing therein; a yieldable resisting member associated with the opposite end of said plunger member and adapted to hold same against movement under predetermined combustion chamber pressures; a cylindrical valve member adapted to floatably fit within said tubular plunger and provided on one end with a valve header adapted to clear the vents in said plunger member when seated therewith and an oil plunger bore on the other end, said bore having spray outlets provided therein in proximity with the valve header for discharging purposes when the latter becomes unseated; yieldable coupling means yieldably coupling said plunger member with said valve member adapted to normally preserve a seated relationship therebetween; a stationary oil delivery tubular plunger member fitting said oil plunger bore of said valve member to permit the valve member to float thereon and opening the bore of the same to the oil supply of the device; and means for delivering oil to the device at a predetermined pressure. 110

18. A fuel oil injecting device for internal combustion engines, comprising a floatable tubular plunger member provided with a 115

- vented valve sealing end which is exposed to the combustion chamber of the engine and floatably operated by the pressures prevailing therein; a yieldable resisting member associated with the opposite end of said plunger member and adapted to hold same against movement under predetermined combustion chamber pressures; a cylindrical valve member adapted to floatably fit within said tubular plunger and provided on one end with a valve header adapted to clear the vents in said plunger member when seated therewith and an oil plunger bore on the other end, said bore having spray outlets provided therein in proximity with the valve header for discharging purposes when the latter becomes unseated; yieldable coupling means yieldably coupling said plunger member with said valve member adapted to normally preserve a seated relationship therebetween; a stationary oil delivery tubular plunger member fitting said oil plunger bore of said valve member to permit the valve member to float thereon and opening the bore of the same to the oil supply of the device; means for delivering oil to the device at a predetermined pressure; and combination means for regulably bypassing oil from said oil plunger to the source of supply or vice versa and for automatically bypassing the oil as aforesaid.
20. A fuel oil injecting device for internal combustion engines, comprising a floatable tubular plunger member provided with a vented valve sealing end which is exposed to the combustion chamber of the engine and floatably operated by the pressures prevailing therein; a yieldable resisting member associated with the opposite end of said plunger member and adapted to hold same against movement under predetermined combustion chamber pressures; a cylindrical valve member adapted to floatably fit within said tubular plunger and provided on one end with a valve header adapted to clear the vents in said plunger member when seated therewith and an oil plunger bore on the other end, said bore having spray outlets provided therein in proximity with the valve header for discharging purposes when the latter becomes unseated; yieldable coupling means yieldably coupling said plunger member with said valve member adapted to normally preserve a seated relationship therebetween; a stationary oil delivery tubular plunger member fitting said oil plunger bore of said valve member to permit the valve member to float thereon and opening the bore of the same to the oil supply of the device; a casing member housing said yieldable resisting member and the free ends of said plunger and valve members and open to the combustion chamber by a duct provided therefor for compensating the cylinder pressures directed against the cylinder ends of said plunger and valve members; a regulable and automatically operated bypass mechanism intercepting said bypass duct for regulably controlling the pressure in said casing member and for automatically exposing same to the full pressure of the combustion chamber, according as may be necessary; means for delivering oil to the device at a predetermined pressure; and means for regulably bypassing oil from said oil plunger to the source of supply or vice versa.
19. A fuel oil injecting device for internal combustion engines, comprising a floatable tubular plunger member provided with a vented valve sealing end which is exposed to the combustion chamber of the engine and floatably operated by the pressures prevailing therein; a yieldable resisting member associated with the opposite end of said plunger member and adapted to hold same against movement under predetermined combustion chamber pressures; a cylindrical valve member adapted to floatably fit within said tubular plunger and provided on one end with a valve header adapted to clear the vents in said plunger member when seated therewith and an oil plunger bore on the other end, said bore having spray outlets provided therein in proximity with the valve header for discharging purposes when the latter becomes unseated; yieldable coupling means yieldably coupling said plunger member with said valve member adapted to normally preserve a seated relationship there-
- between; a stationary oil delivery tubular plunger member fitting said oil plunger bore of said valve member to permit the valve member to float thereon and opening the bore of the same to the oil supply of the device; means for delivering oil to the device at a predetermined pressure; and combination means for regulably bypassing oil from said oil plunger to the source of supply or vice versa.
21. A fuel oil injecting device for internal combustion engines, comprising a floatable tubular plunger member provided with a vented valve sealing end which is exposed to the combustion chamber of the engine and floatably operated by the pressures prevailing therein; a yieldable resisting member associated with the opposite end of said

plunger member and adapted to hold same against movement under predetermined combustion chamber pressures; a cylindrical valve member adapted to floatably fit within 5 said tubular plunger and provided on one end with a valve header adapted to clear the vents in said plunger member when seated therewith and an oil plunger bore on the other end, said bore having spray outlets 10 provided therein in proximity with the valve header for discharging purposes when the latter becomes unseated; yieldable coupling means yieldably coupling said plunger member with said valve member adapted 15 to normally preserve a seated relationship therebetween; a stationary oil delivery tubular plunger member fitting said oil plunger bore of said valve member to permit the valve member to float thereon and 20 opening the bore of the same to the oil supply of the device; a casing member housing said yieldable resisting member and the free ends of said plunger and valve members and open to the combustion chamber by a 25 duct provided therefor for compensating the cylinder pressures directed against the cylinder ends of said plunger and valve members; a regulable and automatically operated bypass mechanism intercepting said by- 30 pass duct for regulably controlling the pressure in said casing member and for automatically exposing same to the full pressure of the combustion chamber, according as may be necessary; means for delivering 35 oil to the device at a predetermined pressure; means for regulably bypassing oil from said oil plunger to the source of supply or vice versa; and combination means for regulably bypassing oil from said oil plunger 40 to the source of supply or vice versa and for automatically bypassing the oil as aforesaid.

22. An automatically controlled fuel injection valve comprising a floatable plunger member exposed to the pressures within the 45 combustion chamber of the engine and adapted to be actuated thereby; a floating oil carrying and discharge member, telescopingly fitting said plunger member, provided with a contracting oil reservoir therein which is 50 open to the oil system of the engine, a check valve between the oil reservoir and the oil

system of the engine, and a sealing header which normally seats with said plunger member for preventing discharge therebetween of oil carried in said oil carrying and 55 discharge member, and yieldable coupling means normally engaging said plunger member with said atomizing valve member to cause the latter to floatably operate in sealed relationship therewith but relatively free to 60 permit said valve member to unseat from said plunger member when the pressure on the oil in the reservoir exceeds the actuating pressure operating said plunger member for effecting the aforesaid atomizing discharge 65 feature.

23. An automatically controlled fuel injection valve comprising a floatable plunger member exposed to the pressures within the combustion chamber of the engine and adapted to be actuated thereby; a floating atomizing valve member, telescoping said plunger member, provided with a contracting oil reservoir therein which is open to the oil system of the engine at one end thereof and to 70 the combustion chamber at the other end, and a sealing valve which normally seats with said plunger member for effecting a closure to said floating valve member and otherwise to unseat for effecting a spray 75 opening therebetween for discharging the oil therethrough; yieldable coupling means normally engaging said plunger member with said atomizing valve member to floatably operate in sealed relationship therewith but 80 otherwise to prevent said valve member to unseat from said plunger member to effect the spray opening therebetween when the pressure in the oil reservoir exceeds the actuating pressure operating said plunger member; 85 yieldable resisting means provided said plunger member adapted to restrict same against motion under a predetermined pressure in the combustion chamber; a spring controlled check valve between the oil system of the 90 engine and the oil reservoir; and a regulable bypass means controlling the relief from the oil reservoir back to the oil supply.

In testimony whereof I hereto affix my signature, this ninth day of February, 1920. 100

WILLIAM BURROUGHS SMITH WHALEY.
